(57) **CLAIM**

I claim the ornamental design for a fluid dispensing lid, as shown and described.

DESCRIPTION

FIG. 1 is a top front right perspective view of a fluid dispensing lid, the present invention, in a closed configuration.

FIG. 2 is a front elevational view thereof.

FIG. 3 is a right elevational view thereof.

FIG. 4 is a rear elevational view thereof.

FIG. 5 is a top plan view thereof.

FIG. 6 is a bottom plan view thereof.

FIG. 7 is a top front right perspective view of the fluid dispensing lid of FIG. 1, in an open configuration.

FIG. 8 is a front elevational view thereof.

FIG. 9 is a right elevational view thereof.

FIG. 10 is a rear elevational view thereof.

FIG. 11 is a top plan view thereof; and,

FIG. 12 is a bottom plan view thereof.

1 Claim, 12 Drawing Sheets
